ILLUMINABLE SIGN

Maxwell O. Wallace, Lansing, Mich., assignor to
General Parts and Service, Lansing, Mich., a
corporation of Michigan

Application November 28, 1949, Serial No. 6,284

Term of patent 7 years

(Cl. D72—1)

To all whom it may concern:

Be it known that I, Maxwell O. Wallace, a citizen of the United States, residing at Lansing, in the county of Ingham and State of Michigan, have invented a new, original, and ornamental Design for an Illuminable Sign, of which the following is a specification, reference being had to the accompanying drawing, forming part hereof, in which:

Figure 1 is a perspective view of an illuminable sign, showing my new design;

Figure 2 is a top plan view thereof, and

Figure 3 is an end elevational view of the same.

The dotted lines shown in the drawing are for illustrative purposes only.

I claim:

The ornamental design for an illuminable sign, as shown and described.

MAXWELL O. WALLACE.
